(57) **CLAIM**

I claim the ornamental design for a combination digital clock and coin collection display, as shown and described.

DESCRIPTION

FIG. 1 is a perspective view of a combination digital clock and coin collection display showing my new design showing a pivotal back stand removed therefrom;

FIG. 2 is a front elevation of the combination digital clock and coin collection display shown in an assembled condition;

FIG. 3 is a rear elevation of FIG. 2;

FIG. 4 is a side elevation as seen from the right side of FIG. 2;

FIG. 5 is a side elevation as seen from the left side of FIG. 2;

FIG. 6 is a top plan view thereof;

FIG. 7 is a bottom plan view thereof; and,

FIG. 8 is a left side elevational view similar to FIG. 4 but showing the removable back stand pivoted outwardly for use.
